SKI STRAP

John Joseph D'Atri, Tahoe Valley, Calif.
(Tahoe Valley, Lake Tahoe, Calif.)

Filed May 11, 1959, Ser. No. 55,852

Term of patent 14 years

(Cl. D34—5)

Fig. 1.

Fig. 2.

Fig. 3.

Fig. 1 is a perspective view of a ski strap showing my design.

Fig. 2 is a plan view of the opposite side.

Fig. 3 is an end view of the ski strap.

The characteristic feature of my design resides in the combination on the ski strap disclosed of a tab which terminates at a point surrounded by a ball, and said strap having beaded edges, three crosswise beaded ribs on the butt end thereof above the beaded slot, all as shown.

I claim:

The ornamental design for a ski strap, as shown and described.
